US00D916920S

(12) **United States Design Patent** (10) **Patent No.:** **US D916,920 S**
Marcinelli (45) **Date of Patent:** **** Apr. 20, 2021**

(54) **DISPLAY SCREEN WITH GRAPHICAL USER INTERFACE**

(71) Applicant: **Bottomline Technologies (de) Inc.**,
Portsmouth, NH (US)

(72) Inventor: **Michael Marcinelli**, North Andover,
MA (US)

(73) Assignee: **Bottomline Technologies, Inc.**,
Portsmouth, NH (US)

(**) Term: **15 Years**

(21) Appl. No.: **29/723,492**

(22) Filed: **Feb. 7, 2020**

(51) **LOC (13) Cl.** **14-04**

(52) **U.S. Cl.** **USPC D14/492**

(57) **CLAIM**

The ornamental design for a display screen with graphical user interface, as shown and described.

DESCRIPTION

FIG. 1 is a front view of a first embodiment of a display screen with graphical user interface;

FIG. 2 is a front view of a second embodiment of a display screen with graphical user interface; and,

FIG. 3 is a front view of a third embodiment of a display screen with graphical user interface.

The dot-dash broken lines illustrate a portion of a display screen and form no part of the claimed design. The dashed broken lines illustrate portions of the graphical user interface and form no part of the claimed design. The graphical user interface could be displayed on the display screen of a computer server, a laptop computer, a mobile phone, a telephone, a tablet, a smart watch, or other electronic device.

1 Claim, 3 Drawing Sheets
